UNITED STATES PATENT OFFICE

148,473

DESIGN FOR A CATALOGUE RACK

Erik P. Krag, Peoria, Ill., assignor to The Frick-Gallagher Manufacturing Company, Wellston, Ohio, a corporation of Ohio

Application September 30, 1946, Serial No. 133,653

Term of patent 7 years

(Cl. D33—2)

To all whom it may concern:

Be it known that I, Erik P. Krag, a citizen of the United States, residing at Peoria, in the county of Peoria and State of Illinois, have invented a new, original, and ornamental Design for Catalogue Rack, of which the following is a specification, reference being made to the accompanying drawing, forming part thereof.

The figure is a perspective view of a catalogue rack, showing my new design.

I claim:

The ornamental design for a catalogue rack, as shown.

ERIK P. KRAM.
